UNITED STATES PATENT OFFICE

LEON A. WATSON, OF CLEVELAND, OHIO, ASSIGNOR TO THE CLARK CONTROLLER COMPANY, OF CLEVELAND, OHIO, A CORPORATION OF OHIO

CONTROLLER CONSTRUCTION

Application filed September 23, 1926. Serial No. 137,332.

The present invention relates to manual controllers for electric machines and more particularly to the construction of the controller proper. In the present construction, 5 use is made of a pressed steel frame for carrying all of the controller parts including the resistance units, and the contact members, and in order to provide the necessary rigidity for the mounting of the operating mechanism, including the operating shaft with its contact arm and the gear train for operating this shaft. A cast spider construction is employed which is secured to the pressed frame structure so as to provide a satisfactory bearing for the shaft and its operating parts. To the accomplishment of the foregoing and related ends, said invention, then consists of the means hereinafter fully described and particularly pointed out in the claims.

20 The annexed drawing and the following description set forth in detail certain mechanism embodying the invention, such disclosed means constituting, however, but one of various mechanical forms in which the principle 25 of the invention may be used.

In said annexed drawing:

Fig. 1 is a rear perspective view of the frame and operating mechanism; Fig. 2 is a side elevational view of such frame, showing in dotted lines the complete unit; Fig. 3 is an elevational view of the spider itself; Fig. 4 is a sectional view through the spider taken on the line 4—4 of Fig. 3; Fig. 5 is a section view through the center of the spider showing the shaft contact arm and operating pinion; and Fig. 6 is a rear elevational view of the frame, and operating mechanism.

The present type of frame construction is particularly adapted for electrical controllers such as are used for controlling hoisting motors as well as alternating current types of motors, and the controller itself consists essentially of a frame which has a base member 1 of pressed steel with a turned down flange so as to space the base plate portion above the bottom of the member and to this base member is attached a vertical supporting member or partition wall 2 provided with flanges 3 extending at right angles to the plane of the wall to aid in making the sup-

port rigid. On this wall member 2 is mounted a top or cover 4 which is also of pressed steel. The top and partition wall are welded together to form an integral unit and the wall together with its side flanges is likewise preferably welded to the base to form a light weight integral frame for the controller parts. On the rear side of the partition wall are ordinarily mounted the resistance units which are, of course, carried on a separate supporting frame which can be attached to the side members or flanges 3, lugs 6 being provided for this purpose. The base is provided with apertures 7 for the attachment of the resistance units. On the forward side of the partition wall, that is the left side, as shown in Fig. 2, is mounted the face plate 8 of the controller with its various contacts over which the contact arm of the controller moves to make and break the various circuits.

The partition wall is preferably provided near the top with two arcuate slots 10 and is also provided with an aperture about which is mounted a cast metal spider 11 which carries the controller operating mechanism. This spider is preferably a casting so as to provide the necessary rigidity to the structure and consists of a circular plate 12 having apertures 13 therethrough and having four radial ribs or spokes 14 connecting the central hub portion 15 with the outer ring 16. This spider is also provided at the top with a hollow extension 17 and there is likewise a similar hollow extension 18 at the bottom. The spider is attached to the partition wall by means of a series of bolts 19 which pass through the wall and into suitable threaded apertures formed in bosses 20 around the outer ring of the spider, these bosses being formed at the ends of the spokes so as to provide as stiff a structure as possible.

The hub 15 of the spider is a hollow extension 25 which is on the forward side of the partition wall and in this extension is mounted the operating shaft 26 for the controller, the shaft being carried in the extension on a plain bearing 27 at one end and on a radial ball thrust bearing 28 at the other end, this thrust bearing 28 being mounted in an enlarged bore 29 formed in the rear face of the 100

hub 15. To form a dust proof bearing, the shaft 26 extends rearwardly beyond the face of the spider and is provided at its rear end with a pinion 30 which is keyed to the shaft, the key 31 being held in by a threaded bolt 32 and a washer 33, and this pinion is provided with a shoulder 34 to receive and hold a dust washer 35 between the face of the pinion and the circular face of the hub of the spider. To the other or forward end of the shaft which extends beyond the spider extension is keyed the contact arm 36 of the controller the key 37 being held in place by a washer 38 which in turn is secured to the end of the shaft by means of a bolt 39.

Mounted in the aperture 40 in the upper extension 17 of the spider is a short stub shaft 41 on which is carried the operating quadrant 42 having gear teeth 43 in mesh with the operating pinion on the shaft and this quadrant extends upwardly to a point adjacent the top of the frame and is provided with a downwardly extending aperture in which the controller handle 44 is fitted, this handle extending through a slot formed in the top plate so as to allow the quadrant to be rocked to rotate the operating shaft in either direction. The lower extension 18 of the spider is provided with the same type of stub shaft 41 as the top extension so as to allow the quadrant to be mounted from the under side of the operating pinion if desired, and when so mounted the operating handle will extend through a slot 45 formed in the base portion 35 of the frame and will extend below this base into an operating position.

By using a pressed steel frame construction for the controller applicant is enabled to eliminate the usual heavy castings which have heretofore been employed, and by mounting a stiff spider on this sheet steel frame, he has been able to obtain the necessary rigidity in the entire structure to properly support the operating shaft, and the gears for rotating the same as well as for supporting the contact arm. The use of a cast steel spider also provides the necessary type of metal at the center of the controller as this metallic central portion is used to obtain the necessary magnetic field for the usual blow out coil which is employed in controllers of this kind. The use of a removable spider also allows a long bearing to be obtained for the operating shaft and further allows the use of a radial thrust bearing at one end which aids in the ease of manually operating the controller and makes it possible to easily dismount all of the parts of the controller if it is necessary to replace any of the operating parts.

Other modes of applying the principle of my invention may be employed instead of the one explained, change being made as regards the mechanism herein disclosed, provided the means stated by any of the following claims

or the equivalent of such stated means be employed.

I therefore particularly point out and distinctly claim as my invention:

1. A frame for electric controllers comprising a pressed sheet metal base, a vertical pressed sheet metal wall having end flanges at right angles to the plane of the wall, said wall having an aperture, a sheet metal top mounted on said wall and said flanges and having an elongated opening therein, a spider attached to said wall about said aperture and provided with a centrally located hollow extension, and having a stubshaft at the top, an operating shaft mounted in said extension, so and carrying a gear, and an operating quadrant mounted on said stubshaft and in mesh with said gear said quadrant being movable in said elongated opening.

2. In electric controllers of the character described, the combination of a sheet metal frame structure including a vertical wall and a top at substantially right angles to said wall, said top having an elongated opening therein, a cast metal spider attached to said vertical wall within the confines of said frame, operating mechanism carried by said spider, and an actuating member in engagement with said mechanism and movable in said elongated slot.

3. In electric controllers of the character described, the combination of a sheet metal frame structure including a vertical wall having an aperture therein, and a top at substantially right angles to said wall, said top having an elongated opening therein, a cast metal spider attached to said vertical wall within the confines of said frame, a lateral hollow extension on said spider received in said aperture, an operating shaft carried by said extension, and an actuating member in engagement with said shaft and movable in said elongated opening.

4. In electric controllers of the character described, the combination of a sheet metal frame structure including a vertical wall having an aperture therein, and a top at substantially right angles to said wall, said top having an elongated opening therein, a cast metal spider attached to said vertical wall within the confines of said frame, said spider providing a plurality of transverse journals, an operating shaft mounted in one of said journals and an actuating member for said shaft mounted in another of said journals, said member being movable in said elongated opening.

5. In electric controllers of the character described, the combination of a sheet metal frame structure including a vertical wall having an aperture therein, and a top at substantially right angles to said wall, said top having an elongated opening therein, a cast metal spider attached to said vertical wall within the confines of said frame, a lateral hollow

extension on said spider received in said aperture, an operating shaft journaled in said extension, a second extension provided on said spider, and an actuating member mounted on said last named extension, said member being movable in said elongated opening and connected to said shaft.

Signed by me this 21st day of Sept., 1926.
LEON A. WATSON.
